CLAIM

The ornamental design for the dispensing device, as shown and described.

DESCRIPTION

FIG. 1 is a perspective view of the dispensing device; FIG. 2 is a perspective view of the dispensing device of FIG. 1 with the top bin open; FIG. 3 is a perspective view of the dispensing device of FIG. 1 with the bottom bin extended; FIG. 4 is a perspective view of the dispensing device of FIG. 1 with the shelf extended; FIG. 5 is a front view of the dispensing device of FIG. 1; FIG. 6 is a back view of the dispensing device of FIG. 1; FIG. 7 is a left side view of the dispensing device of FIG. 1; FIG. 8 is a right side view of the dispensing device of FIG. 1;

FIG. 9 is a top view of the dispensing device of FIG. 1; and, FIG. 10 is a view from below the dispensing device of FIG. 1.

Broken lines in the drawings illustrate unclaimed portions of the design and form no part of the claimed design.

1 Claim, 10 Drawing Sheets
